UNITED STATES PATENT OFFICE.

JOHN AMES, JR., OF TOLEDO, OHIO, ASSIGNOR OF ONE-HALF TO JOSEPH C. BONNER, OF SAME PLACE.

BRUSH.

SPECIFICATION forming part of Letters Patent No. 349,296, dated September 21, 1886.

Application filed December 16, 1885. Serial No. 185,848. (No model.)

To all whom it may concern:

Be it known that I, JOHN AMES, Jr., of Toledo, Lucas county, Ohio, have made certain new and useful Improvements in Brushes, of which the following is a specification, reference being had to the accompanying drawings.

As is well known, there are two distinct species of brushes manufactured for different uses, and made upon different plans, to wit: 10 One is known as "set work," in which the material of the brush proper is either laid on and around a brush-head, which is usually, but not always, circular, and then is secured in place by means of cords or wires wound around it, or else is stuck into holes in the head and held there by means of pitch or other adhesive substance. Paint-brushes, whitewash-brushes, feather dusters, &c., are examples of this species of brushes. Ordinary brooms are also 20 made on this general plan. Sometimes these set-work brushes, in addition to having the brush materials stuck into holes in the brush-head, are also wound or clamped around the outside, to aid in holding them in place, and to 25 somewhat compact them and keep them from getting misshapen in using. In artists' brushes a metallic thimble or holder is employed. In the manufacture of these set-work brushes the brush-heads are not usually or preferably bored 30 entirely through for setting in the brushing materials, because it is not necessary or desirable. In some cases the brush-heads have been given what may be termed a "stepped-cone" form to facilitate laying on the brushing 35 materials in different layers of different lengths of stock. A good example of such form of brush-head is shown in United States patent of D. W. Lapham, No. 120,523, of October 31, 1871. Again, stepped brush-heads have been 40 made, not conical, with annular ledges to facilitate boring the holes in the heads for setting in the brushing materials. A good example of such form of brush-head is shown in the patent of G. M. Richmond, No. 227,837, of May 45 18, 1880. The other species of brushes is known as "drawn work," and is made in an entirely different way for different uses, and usually by different manufacturers. Drawn work is that in which a brush-block is used which is bored 50 entirely through to receive the brushing materials, (bristles,) and these materials are bent

and doubled in the middle, then drawn into the holes by means of wires or cords, that extend out through the holes at the bottom or back part of the block, and are there fastened, 55 the wires or cords being the means for drawing in and securing in place the brushing materials. Thus it will be perceived there are two distinct arts of brush-making.

My invention relates exclusively to improvements in drawn work.

Heretofore in making drawn work the usual method, or the latest one now generally in vogue, is as follows: A brush-block is formed either flat or convex on its upper surface, and the 65 holes bored through it in rows. Then the bristles or brushing materials are drawn in and secured by wires or cords at the back of the block, as above explained. This block is then fastened to a back, which is provided with a 70 handle, either by means of screws or adhesive substance.

In the drawings, Figures 1 and 2 serve to illustrate these two varieties of manufacture of drawn-work brushes. Now, the objection to these brushes thus made is that in both the bristles or stock used are of the same length in a given brush, and the brushes are more costly for that and other reasons than they should be. In flat brush-blocks, as shown in Fig. 1, where 80 the faces of the brushes are also flat when finished, it is obvious that the bristles must be of about the same length, the only difference being the very slight one which might come from a different inclination of the different tufts of 85 bristles in the same brush; but, practically, where flat-surfaced brush-blocks have been used, the holes have been bored and the bristles inserted substantially at right angles to the flat surface, the outer rows perhaps inclining outward a very little. This, however, does not make any appreciable difference in the length of stock employed in different parts of the same brush—in fact, does not make any difference at all in economy of manufacture, 95 because for such slight variations of lengths of bristles it does not pay to select, and is not practicable to employ assortments of different lengths of stock, as it is furnished commercially at varying prices, due to varying lengths. 100 Where convex-surfaced brush-blocks have been used, all the holes have generally been

bored and the bristles inserted at an incline, or radially, as shown in Fig. 2, so as to be of substantially the same lengths in all parts of a given brush. The object of using and the 5 only result of using a centrally-raised brush-block heretofore has been to get a brush with its face or brushing surface of convex form, like its brush-block.

It is the object of my improvements to provide for the use of short stock, which is much cheaper, in the central part of the brush, to reduce the cost, and improve the make-up of this entire class of drawn-work brushes.

It will be perceived from the foregoing that 15 one of the results I seek and accomplish—that of making a drawn-work brush with its central stock of a different length commercially and practically and of materially different cost—is not reached in either a flat-surfaced 20 or a convex-surfaced brush-block as heretofore employed in drawn-work brushes. I never use a flat-faced brush-block. Whether I make a flat-faced or a convex or rounded faced brush, I always employ a brush-block 25 raised in the center and flat around its margin, the raised central portion never beginning at the edges of the block, however, as heretofore, but always commencing, whatever be the conformation of its surface, at a sufficient distance 30 from the edges to leave a flat margin wider than that required to receive the outer row of bristles. This enables me to employ shorter stock in the center than at the margin of the brush, as I will explain in detail.

35 In the drawings, Figs. 1 and 2 are cross-sections of brushes as heretofore made and put upon the market. The other following figures illustrate my improvements, Fig. 3 being a perspective view of a brush embodying my improvements. Fig. 4 is a view of the back of a brush in process of being united to the brush-block which carries the bristles. Fig. 5 is a cross-section of Fig. 3, and Fig. 6 is a cross-section of Fig. 4. Fig. 7 is a cross-section of a brush-block, of which the raised central portion, instead of being curved on its face, is stepped. Fig. 8 is a similar cross-section, of which the raised central portion of the brush-block is convex or curved on its face.

50 Referring to the letters upon the drawings, Figs. 3 to 8, inclusive, A indicates in Fig. 4 a brush-back before it is shaped, the dotted lines indicating how it is finished to form a handle after being united by means of clamps B to the 55 brush-block C. (Shown in section in Figs. 7 and 8.) By reference to Figs. 7 and 8 it will be seen that the brush-block is provided with a flat margin, D, all around it, and that it has a raised inner or central portion, E, in Fig. 7, and E' in Fig. 8, beginning at the inner limit of the flat margin, and is concave on the back side. The object of constructing a brush-block in this manner and the advantages of such a construction I will now point out. The flat 60 margin D is made for two purposes:

First. To enable the brush-block, after the bristles have been secured to place in it, in the

usual manner, to be clamped tightly all around to the brush-back, and the parts caused to firmly adhere together by means of glue or other suitable cementing or adhesive substance. By this means a very tight joint is secured, as in the best cabinet-work, which, when the brush is finished, is generally entirely or almost imperceptible. Heretofore brush-blocks with 75 raised or convex surfaces have not been constructed with such a flat margin to enable these parts to be united economically and advantageously in this manner; but the convexity or curvature has begun at the outer edges of the 80 brush-block all around. The result has been that clamps, when used, would indent and deform the work; hence resort has been had to screws, which are costly and unsightly, and do not make a tight and invisible joint between 85 the block and back. The clamps pressed against the outer bristles and injured them; and, again, they could seldom be prevented from slipping off, and with brush-blocks of much convexity they could not be used at all, 90 and screws had to be employed.

Second. Besides these advantages of the flat margin around the brush-block, there is another material one relating to the insertion of the outer row of bristles. Heretofore with convex or curved face brush-blocks it has been necessary to bore all the holes for the bristles substantially in a radial relation to the curved surface, in order to avoid the slipping of the bit-point and the production of irregular rows 100 of holes, which, if only slightly perceptible in the block itself, would be very manifest upon observing the outer ends of the bristles of the finished brush. By boring the holes radially all over the convex surface, including the holes 105 for the outer row of bristles, regular rows and evenly-finished work could be produced. By reason of having the margin around the edge of my raised-face brush-block I can bore the first row of holes near the angle formed by the 110 marginal surface and beginning of the raised surface at a less inclination than the outer inclination of the adjacent or second radial row of holes, as well as all the other rows out of which the bristles project radially from the convex raised central portion. This is well shown 115 in the section, Fig. 8, where it will be observed that the distance between the bottoms of the bristles of the first and second rows is greater than the distance between the bottoms of the 120 bristles of the interior rows. Now, on this account the bristles used in the outer row, being so much less inclined than the others, are in better position for use, and the appearance of the brush is greatly improved.

125 In some cases I make my flat-margined brush-block of stepped form in its central raised portion. This is when I desire to make certain kinds of brushes in which the rows of bristles are substantially perpendicular to the brush and parallel to one another. Ordinary cloth-brushes, shoe-brushes, &c., are examples of this species of brushes. In forming these stepped surfaces upon the raised central por-

tions of the brush-blocks I do not wish to be understood as limiting myself to steps that are strictly right-angular in their vertical and horizontal surfaces; but some slight variation from the right-angular relation of these surfaces may be made in some instances. The advantages of this stepped form are, that I can use brush-stock of materially different lengths, and thus attain an important economy in the manufacture of drawn-work brushes in this way. Besides this, the stepped form facilitates the boring in the direction vertical to the body of the brush, which is not convenient upon a convexed surface for the reason already stated—to wit, that the points of the bit in boring such a surface, unless the direction be radial to it, are liable to slip and result in uneven and irregular work. It will be obvious that by this method of making drawn-work brushes, in which the rows of bristles are substantially perpendicular and parallel to each other, what is known in the trade as a "solid brush" can be very successfully made with great economy.

Of course I do not claim, broadly, a stepped surface, but believe I am the first to apply such a surface to use in making drawn work in the manner above set forth. 25

Having thus described my improvements, what I claim to be new, and desire to secure by Letters Patent of the United States, is— 30

1. As an improvement in the manufacture of brushes, a brush-block provided with a flat margin, D, and a raised central portion, substantially as and for the purposes set forth.

2. As an improvement in the manufacture of brushes, a brush-block provided with a flat margin, D, and a raised central portion stepped as described, substantially as and for the purposes set forth. 35

In testimony whereof I have hereunto subscribed my name. 40
